At Attorney's

UNITED STATES PATENT OFFICE.

OLAF L. HOWE, OF MISSOULA, MONTANA.

WATER-MOTOR.

1,312,326.

Specification of Letters Patent.

Patented Aug. 5, 1919.

Application filed February 12, 1917. Serial No. 148,070.

To all whom it may concern:

Be it known that I, OLAF L. HOWE, of Missoula, in the county of Missoula and State of Montana, have invented certain new and useful Improvements in Water-Motors; and I do hereby declare the following to be a full, clear, and exact description of the invention, such as will enable others skilled in the art to which it appertains to make and use the same.

The object of my invention is to provide an improved type of water motor comprising a frame on which the vane carrier is movable so that the vane carrier may, by manual operation, or by force of obstructions, be swung into an inoperative position.

A further object is to render the frame movable so that it may be swung vertically out of the stream, carrying the vane carrier with it so as to withdraw the entire apparatus from the stream.

In the accompanying drawings, Figure 1 is a view in perspective. Fig. 2 is an elevation taken from the dart A, Fig. 1, the full lines showing the motor immersed and the dotted lines showing it withdrawn from the stream. Fig. 3 is a top plan view. Figs. 4 and 5 are details.

In the embodiment of the invention illustrated, I employ a frame which is designed to be located adjacent the bank of a stream, such frame being of skeleton form and having uprights 2 and horizontally disposed connecting timbers 3 and 4, the latter being arranged in pairs. The frame as a whole may be raised and lowered on a bulk-head, pier or string piece, such as 5, appropriately supported on the bank. The uprights 6 of the pier or other supporting member form a guiding means for the frame, timbers 4 of the latter being spaced apart to receive the uprights. Roller bearings 7 are provided on vertical timbers of the frame adjacent the uprights 6 to lessen friction between the frame and the pier in raising and lowering the former. The frame is maintained in desired position in part by bolts 8 passing through timbers 4 and the uprights of the pier, and in part by ropes or cables 9 at each side of the frame, such ropes or cables passing upwardly and over sheaves 10 on the uprights 6. These cables are preferably connected with a windless (not shown). The bolts 8 also serve as pivots when it is desired to swing the frame upwardly through the instrumentality of the windless and cables.

12 designates the vane carrier which is shown as pivotally supported at one end upon the frame 1. A circular track 13 of channel form, which is itself bolted or otherwise secured to the frame, gives additional support to the vane carrier, rollers 14 on the underside of the latter taking in the channel of the track. The vane carrier may be in any preferred form. It is illustrated in the form of an elongated beam upon which are mounted the shafts of a plurality of vanes 15, these shafts being connected by suitable chains and sprockets 16, 17, so as to transmit the power derived from the current to a motor (conventionally indicated at A), mounted on a superposed platform 18 at the inner end of the vane carrier. An additional vane 19 may be provided near the extreme inner end of the carrier, it, like the other vanes, being connected to the common point of power transmission. Protecting bars 20 are suitably secured to the vane carrier, being spaced apart from the vanes so as to ward off the contact of flotsam with the vanes.

Movement of the vane carrier about its pivot under the influence of the current is controlled by a cable 25 which extends over sheaves 26 and 27 on the frame 1 and a third sheave 28 on the top of one of the uprights, the cable being connected to a weight 29 at its other end. It will be seen that the weight 29 through the cable 25 holds the vane carrier in the desired position as against the force of the current moving in the direction of the dart, Fig. 1. At the same time provision is made for the vane carrier swinging out of the path of the current into the dotted line position of Fig. 3 to allow the free movement of heavy flotsam that may encounter the motor. As this movement is against the force of the weight 29 the vane carrier will swing back into its normal position as soon as the obstruction is removed. If it be desired to move the vane carrier into the dotted line position of Fig. 3 it is only necessary to raise the weight 29 which leaves the vane carrier free to swing under the force of the current. As long as the weight remains down, however, its tendency is to hold the vane carrier in the full line position of Fig. 3.

In order to raise the entire structure, that is the frame and the vane carrier 12 out of the stream power is applied to the cables 9, interfering bolts in the frame work having

been first disconnected. The frame will then swing about the pivots 8 into the dotted line position shown in Fig. 2. If desired the vane carrier may be swung so as to lie in practical parallelism with the bank of the stream before the frame is turned on its pivot.

It will be apparent to those skilled in the art that the described structure enables me 10 to use the motor under practically all conditions as very simple means is provided for placing the motor in or out of operative position as well as adjusting it vertically according to the depth of the stream. The 15 vane carrier has no permanent attachment to the bank of the stream nor does it rest upon the bottom of the stream. It automatically gives way under the pressure of flotsam.

20 I claim as my invention:

1. In a water motor, a frame, a vane carrier mounted on and projecting outwardly from said frame, said carrier being adapted for horizontal turning on said frame, a 25 shore support for said frame, means for vertically adjusting the frame on said shore support relative to the current, said means forming a pivotal connection between said frame and said support to permit of the 30 raising of said frame from the water.

2. In a water motor, a frame having a horizontally disposed track or runway, a vane carrier mounted on said track, a shore support for said frame, means for vertically

adjusting said frame on said shore support 35 relative to the current, said means forming a pivotal connection between said frame and said support to permit of the raising of said frame from the water.

3. A water motor, the combination with a 40 shore support having a weight, and a cable attached to said weight, a frame having a circular track or runway, a vane carrier mounted on said track and adapted to swing horizontally in an arc, said cable being secured to said vane carrier, means for vertically adjusting said frame on said shore support relative to the current, said means forming a pivotal connection between said 45 frame and said support to permit of the 50 raising of said frame from the water.

4. In a water motor, the combination with a shore support having a weight and a cable secured to said weight, of a frame pivotally mounted on said support, and a vane carrier mounted on said frame and adapted to swing horizontally in an arc, said cable being secured to said frame to swing the latter and the vane carrier in a vertical plane out of 55 the stream.

60 In testimony whereof I have signed this specification in the presence of two subscribing witnesses.

OLAF L. HOWE.

Witnesses:

HARRY S. BATES,

P. F. SOFFNES.
